UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SWITCH CONSTRUCTION.

Application filed May 18, 1925. Serial No. 30,946.

My invention relates to switch construction.

One of the objects of my invention is to provide a flat type of switch which will be suitable for use in a shallow box.

A further object of my invention is to provide a switch which will be durable and efficient.

Further objects will appear from the description and claims.

In the drawings, in which my invention is illustrated:

Figure 1 is a front view showing the switch and fuses in position in a shallow box;

Fig. 2 is a section on the line 2—2 of Fig. 1;

Fig. 3 is a view similar to Fig. 1, but showing the switch open;

Fig. 4 is a section on the line 4—4 of Fig. 1;

Fig. 5 is a section on the line 5—5 of Fig. 1;

Figs. 6 and 7 are views showing the action of the switch lever and associated parts;

Fig. 8 is a section on the line 8—8 of Fig. 1;

Fig. 9 is a section on the line 9—9 of Fig. 1; and

Fig. 10 is a perspective view of the actuating slide.

Referring to the drawings in detail, the construction shown therein comprises an insulating base 1, terminal lugs 2 for the line connections, cartridge fuses 3 between the terminals, and a double pole, double break switch construction for controlling the circuit between the terminals.

The switch construction shown comprises a pair of switch arms 4, each pivotally mounted intermediate its ends, a reciprocable actuating slide 5 movable back and forth between the switch arms 4, a pair of insulating links 6 pivotally connecting the slide with the switch arms respectively, a manually operable switch lever 7 oscillatable back and forth, and a tension spring 8 connecting the switch lever 7 with the actuating slide 5.

The actuating slide 5 is provided with a pair of detent and positioning rollers 9, the slide being provided with two pairs of depressions 10, one pair cooperating with each roller.

In operation, when the switch lever 7 is moved from the position shown in Fig. 6 to the position shown in Fig. 7, the tension of the spring holds the slide 5 upwardly against the rollers 9, each of which is seated in one of the depressions in the slide, and the co-action of the spring rollers and depre-

sions is such that the rollers hold the slide against movement until the switch lever has been moved far enough to cause considerable spring pressure to be exerted in a direction to cause the slide to move to the right. When the spring tension has accumulated sufficiently to move the slide against the holding action of the rollers, the slide moves with a quick snap action to the position shown in Fig. 7. This lateral movement of the slide necessitates a slight downward movement also to permit the slide to escape from the holding action of the rollers. When the switch lever moves from the full line position shown in Fig. 7 to the full line position shown in Fig. 6, a similar snap action of the actuating slide takes place due to the co-action between the detent rollers and the two left-hand depressions. This snap action of the slide of course indicates a quick snap action to the two switch arms 4.

Any suitable interlocking construction may be provided between the switch lever and the hinged cover 11 so that the switch cannot be closed when the cover 11 is open, or the cover opened when the switch is closed. In the construction shown, opening of the door is prevented when the switch is closed by the engagement of the switch lever 7 with the cover 11. Similarly when the switch is open it is prevented from being closed so long as the cover 11 is open by the engagement of the edge of the slot in the cover with the switch lever 7.

Each of the oscillatable switch arms comprise a pair of switch blades 12 (Figs. 8 and 9) for engagement with opposite sides, respectively, of the cooperating fixed contacts 13, a plurality of spacers 14 intermediate these switch blades 12, a pair of leaf springs 15 bearing on the blades 12, respectively, tending to force the blades toward each other, and a pair of screws 16 extending through the leaf springs and switch blades and threaded into nuts 17 for adjustably holding the leaf springs pressing against the switch blades. Each switch arm is oscillatably mounted on a bushing 18 secured to the insulating base 1 by means of a screw 19 and lock-nuts 20.

The fixed contacts 13 are provided with bevelled edges 21 to facilitate the engagement of the switch arms therewith.

Each cartridge fuse is provided with a pair of contact clip devices, each of these contact

- clip devices comprising in addition to one of the switch contact members 13 previously referred to, a U-shaped leaf spring member 22 and an L-shaped clamping member 23. 6 The contact tip 24 of the cartridge fuse enters between the switch contact member 13 and the leaf spring member 22 and is yieldingly and clampingly held against the fuse contact by means of the L-shaped clamping member 23 and the clamping screw 24 and nut 25.

While I have described but one embodiment of my invention it is obvious that many modifications therein may occur to those skilled in the art, and I desire, therefore, 15 that my invention be limited only by the scope of the appended claims and by the prior art.

Having described my invention what I 20 claim as new and desire to secure by Letters Patent of the United States is:

1. A switch construction comprising a flat base and a double pole switch having a pair of switch arms which are oscillatably 25 mounted to swing about axes perpendicular to the plane of the base and common means for simultaneously actuating said switch arms, said common means comprising a member 30 slidable in a general plane parallel to the plane of the base and connections between said slidable member and said switch arms, respectively.

2. A switch construction comprising a flat base and a double pole switch having a pair 35 of switch arms which are oscillatably mounted to swing about axes perpendicular to the plane of the base and common means for simultaneously actuating said switch arms, said common means comprising a member 40 slidable in a general plane parallel to the plane of the base and a pair of links pivotally connecting said slidable member and said switch arms, respectively.

3. A switch construction comprising a flat 45 base and a double pole switch having a pair of switch arms which are respectively oscillatably mounted to swing about axes perpendicular to the plane of the base, common means for simultaneously actuating said 50 switch arms comprising a member movable in a plane parallel to said base, a movable spring for actuating said member, and a releasable holding member for holding said member against movement during part of the 55 spring movement, which when released permits a snap action of the spring and member.

4. A switch construction comprising a flat base and a double pole switch having a pair 60 of switch arms which are respectively oscillatably mounted to swing about axes perpendicular to the plane of the base and common means for simultaneously actuating said switch arms, said common means comprising a member slidable in a general plane parallel 65 to the plane of the base, a manually operated

member and a spring connecting said sliding member and said manually operated member.

5. A switch construction comprising a stationary contact blade, a pair of pivotally mounted contact blades, movable as a unit, the ends of said movable blades straddling the stationary blade when the switch is in "on" position, and a pair of leaf springs embracing between them the pivotally mounted blades, and movable therewith and having end bearing portions exerting yielding pressure on those portions of the movable contact blades which engage the stationary blade, and means for adjusting the spring pressure comprising a screw extending through said movable contact blades and springs at a point between the pivotal mounting of the blades and end bearing portions of the leaf spring. 70

6. A switch construction comprising a stationary contact blade, a pivot pin, a pair of contact blades pivoted on said pivot pin and movable as a unit, the ends of said movable blades straddling the stationary blade when the switch is in "on" position, and a pair of leaf springs embracing between them the pivotally mounted blades and movable therewith and exerting yielding pressure on those portions of the movable contact blades which engage the stationary blade, said pivotal pin 80 extending through said leaf spring. 85

7. A switch construction comprising a flat base, a pair of switch blades, respectively oscillatably mounted to swing about axes perpendicular to the plane of the base, an operating switch lever oscillatable about an axis parallel to the base and transmission from said switch lever to each of said switch blades. 100

8. A switch construction comprising a flat base, a pair of switch arms oscillatably 105 mounted thereon, each switch arm being pivoted intermediate its ends, two pairs of stationary contacts, one pair for each end of the switch arm whereby each switch arm effects a double break in series, and common means for simultaneously actuating both said switch arms comprising a member slidable in a plane parallel to the plane of the base and connections between said slidable member and said switch arms, respectively. 110

9. A switch construction comprising a switch blade, a shiftable member having a recess therein for actuating said blade, an actuating member, a spring connecting said actuating member and shiftable member, and a roller detent engaging the recess in said shiftable member, said spring tending to hold said shiftable member against said roller in one position of the actuating member but acting in a direction which releases said shiftable member from said roller detent when the actuating member has been moved a predetermined amount. 115

10. A switch construction comprising a switch blade, a shiftable member having a 120

- recess therein for actuating said blade, an actuating member, a spring connecting said actuating member and shiftable member, and a roller detent engaging the recess in said shiftable member, said spring tending to hold said shiftable member against said roller in one position of the actuating member but acting in a direction which releases said shiftable member from said roller detent
- 10 when the actuating member has been moved a predetermined amount, said actuating member engaging said shiftable member to give it a positive release if the spring action fails to release it.
- 15 11. A switch construction comprising a switch blade, a shiftable member having a recess therein for actuating said blade, an actuating member, a spring connecting said actuating member and shiftable member, and
- 20 a roller detent engaging the recess in said shiftable member, said spring tending to hold said shiftable member against said roller in one position of the actuating member but acting in a direction which releases said shiftable member from said roller detent when the actuating member has been moved a predetermined amount, said actuating member engaging said shiftable member to press it away from said roller and release it if the spring
- 25 action fails to release it.
12. A switch construction comprising a pair of stationary contact blades, a pair of contact blades pivotally mounted intermediate their ends and movable as a unit so
- that their ends straddle said stationary blades and a pair of leaf springs straddling said movable blades and movable therewith and extending substantially from end to end thereof and having end bearing portions exerting yielding pressure on those portions of said movable blades which engage the stationary blades and means for adjusting the spring pressure comprising screws extending through said movable blades and springs at points between said pivotal mounting and the said end bearing portions.
- 30 13. A switch construction comprising a pair of stationary contact blades, a pair of contact blades pivotally mounted intermediate their ends and movable as a unit so
- 50 that their ends straddle said stationary blades and a pair of leaf springs straddling said movable blades and movable therewith and extending substantially from end to end thereof and having end bearing portions exerting yielding pressure on those portions of said movable blades which engage the stationary blades and means for adjusting the spring pressure comprising screws extending through said movable blades and springs at
- 55 points between said pivotal mounting and the said end bearing portions and means for pivotally mounting said movable blades comprising a pivotal pin extending through said movable blades and springs.
- 60 In witness whereof, I have hereunto subscribed my name.
- 65 REUBEN B. BENJAMIN.
